Notchett, Hill

UNITED STATES PATENT OFFICE.

EDWARD W. HILL, OF CHICAGO, ILLINOIS.

COMBINED PENCIL AND PENCIL-SHARPENER.

1,228,672.

Specification of Letters Patent. Patented June 5, 1917.

Application filed May 17, 1916. Serial No. 98,064.

To all whom it may concern:

Be it known that I, EDWARD W. HILL, a citizen of the United States of America, residing at Chicago, Illinois, have invented a new and useful Combined Pencil and Pencil-Sharpener, of which the following is a specification.

My present invention has reference to pencils and general objects of the invention 10 are to combine with a pencil a simple and practical lead pointing device which when not in use will be ordinarily carried by and form a part of the pencil and which can be conveniently operated at any time to sharpen 15 the lead.

In accomplishment of these objects I employ a sharpening device which is constructed to fit over and receive the point end of the pencil and provide the pencil with 20 supporting means for normally supporting and confining the sharpener to the pencil end.

A special feature of the invention is the provision of the sharpener with a lead guide 25 at the inner end of the socket therein which receives the point end of the pencil for supporting and bracing the protruding end of the lead as the lead is being pointed.

Another feature of the invention is a 30 pencil sharpening blade which is mounted at the inner end of the socket in the blade holder and is provided with a V-shaped notch in line with the socket and having a sharpening edge arranged to sharpen the 35 lead by the rotation of the blade holder in either or both directions.

Various other features and details of construction will appear as the specification proceeds.

40 In the accompanying drawing I have illustrated the invention embodied in a practical and preferred form but I would have it understood that changes and modifications may be made without departing from the 45 true spirit and scope of the invention.

In said drawing:

Figure 1 is an enlarged view of a so-called "magazine" or "clutch" pencil constructed in accordance with and embodying the invention.

Fig. 2 is another view of the same showing the blade holder removed from its support at the end of the pencil and applied to the point end of the pencil in the act of sharpen-

ing the lead, the lead holder being in this 55 view shown in section.

Fig. 3 is a vertical sectional view taken substantially on the line 3—3 of Fig. 1.

Fig. 4 is a detached perspective view of the blade.

Figs. 5, 6, 7 and 8 are enlarged sectional views of different forms of blades taken substantially on the plane of the line 5—5 of Fig. 4.

In the present disclosure I have shown my 65 invention as applied to a "magazine" or "clutch" pencil of more or less conventional structure embodying a body portion 7 terminating in a casing or tip 8 inclosing and protecting the end portion of the lead 9, said 70 tip portion of the pencil having a clutch therein for gripping or holding the lead.

The opposite end of the pencil is provided with a support for the sharpener and this support takes the form, in the present 75 disclosure, of a screw threaded stud or projection 10, which is shown secured to the end of the pencil body and having a stem 11 projecting in the end of the pencil body and an outstanding flange 12 engaging the 80 end of the pencil body.

The sharpening device consists, in the 85 illustration, of a holder 13 supporting a sharpening blade 14, said holder being provided with a socket 15 in one end thereof to loosely receive the lead inclosing casing of the pencil and the blade being shown formed with the V-shaped notch 16 therein in line with the socket and having its edges sharpened to afford the cutting edges. In the 90 specific construction shown the support for the sharpener is a screw threaded stud and the inner walls of the socket 15 therefore are screw threaded as indicated to receive and fit the screw threads of the threaded 95 supporting stud 10. This threaded supporting stud is of slightly larger diameter than the tip of the pencil so that the socket will have a loose fit thereover to prevent the screw threaded inner walls of the socket 100 from scratching the tip or lead inclosing casing 8, the screw threads being preferably flattened as indicated at 17 so as to leave no sharp edges inside the socket.

At the inner end of the socket 15 is preferably provided a guide 18 for receiving and bracing the lead, this guide being shown as a separate bushing seated in the inner

end of the socket. This lead guide has a beveled seat 19 at the entrance thereto to receive the somewhat beveled or rounded end of the lead inclosing casing 8. To facilitate the insertion of the tip of the pencil in the sharpener the mouth of the socket may be beveled as indicated at 20.

The lead sharpening blade is shown secured in its holder by seating it in a slot 21 formed in the outer end of the holder, a screw 22 being provided for clamping the two thus-separated portions of the holder together upon the blade therebetween, said screw passing through an opening 23 provided in the blade. Lateral displacement of the blade is prevented in the blade holder by providing positioning shoulders 24 at the inner end of the slots 21 engaging the beveled end portions 25 of the blade.

Fig. 5 shows in detail how the opposite edges of the V-shaped notch in the blade are beveled to provide the cutting edges 26 and 27 and these edges are shown arranged so that when the cutter is rotated right-handedly the cutting edge 27 will be effective and when rotated left-handedly the cutting edge 26 will be effective. This construction enables the sharpening of the lead by alternate relative rotation of the pencil and sharpener in opposite directions. The blade shown in Fig. 6 is also sharpened to cut in both directions, while those shown in Figs. 7 and 8 are right handed and left handed cutting blades.

Ordinarily it will be seen that the sharpener is carried by and actually forms a part of the pencil, it being usually made more or less ornamental in appearance so as to add to rather than detract from the appearance of the pencil. When the lead becomes dulled as indicated in Fig. 1 the sharpener is simply removed from its support on the end of the pencil, the point of the pencil is inserted in the socket of the sharpener and upon relative rotation being set up between the pencil and blade holder the lead is quickly sharpened. With the cutting edges arranged as shown it is possible to sharpen the pencil by alternate rotative movements in opposite directions, making it convenient in the sharpening operation to hold the pencil between the fingers of one hand and the sharpener between the fingers of the other hand and then twirl the two elements thus held in the fingers in opposite directions or twirl one while holding the other relatively stationary. Ducts or passages 28 are usually provided at the opposite sides of the cutting blade for carrying off the lead shavings.

While my invention is applicable to pencils generally, it is of particular utility in connection with pencils of the "clutch" type for the reason that with such pencils it is usually considered necessary to use a rela-

tively hard lead to prevent the "clutch" from cutting into and breaking off the lead and it has always been a matter of some difficulty heretofore to keep a sharp point on such relatively hard leads. My invention it will be seen provides a simple and always accessible means for quickly sharpening such leads. The lead guide is particularly important in this connection in that it centers the cutter on the lead and at the same time braces the lead so as to prevent breakage thereof.

What I claim is:

1. The combination with a lead carrier having a lead inclosing casing at the point end thereof and a projecting stud of slightly larger diameter than said lead inclosing casing at its opposite end, of a blade holder provided with a socket in the end thereof closely engaging the protruding stud on the end of the lead carrier to thereby secure said blade holder to the lead carrier and said socket being adapted when disengaged from the lead carrier to freely receive the lead inclosing casing on the opposite end of the lead carrier to thereby guide and rotatably support the point end of the lead carrier within said blade holder and a lead sharpening blade at the inner end of the socket in the blade holder.

2. A lead sharpener for clutch pencils comprising a blade holder having a substantially cylindrical longitudinally extensive socket in one end thereof provided with relatively rigid longitudinally extending walls adapted to embrace and house a pencil casing and thereby rotatably confine said pencil casing in said holder and provided with a lead receiving guide at the inner end of said pencil-casing socket in axial alignment with the socket, said holder further having a longitudinal slot therein extending inward from the opposite end of the blade holder to said lead guide and a cutting blade seated in said slot and provided with a cutting edge in line with the lead guide, all whereby the pencil casing and lead are rotatably centered in the sharpener and relative angular movement of the pencil and sharpener is prevented by engagement of the pencil casing with the rigid longitudinal inner walls of the socket in the end of the blade holder in conjunction with the similar supporting of the lead in the lead guide, and independently of any support afforded by the cutting blade.

3. The combination with a lead carrier having a lead inclosing casing at the point end thereof and a screw threaded stud of slightly larger diameter at its opposite end, of a blade holder having an internally screw threaded socket in one end thereof to receive and engage the screw threaded stud, the screw threads on the inner walls of said socket having blunt edges to allow for free

and unrestricted rotation of the point of the pencil within the socket and to prevent scratching of such point in the socket and a lead sharpening blade at the inner end of 5 the socket in the holder.

4. The combination with a pencil having a lead inclosing casing at the point end thereof and a screw threaded stud of slightly larger diameter at the opposite end

10 thereof, of a blade holder having a screw threaded socket receiving and fitting the screw threaded stud whereby said blade holder is normally confined to and carried by the pencil, said socket loosely receiving 15 the lead inclosing casing at the point end of the pencil whereby the point of the pencil may be rotated in the blade holder, said blade holder having a guide at the inner end of the socket therein receiving and bracing

20 that portion of the lead projecting beyond the lead inclosing casing and a lead sharpening blade mounted in the blade holder at the end of the lead guide aforesaid.

5. In a device of the character set forth, a 25 holder having a socket in one end thereof and a longitudinal slot in the opposite end extending longitudinally to said socket and separating the end portion of the holder into two parts, a cutter blade seated in said 30 slot and having a cutting edge disposed within the socket and means for clamping the two separated end portions of the holder together upon the blade therebetween.

6. In a device of the character set forth, a 35 holder having a socket in one end thereof and a longitudinal slot in the opposite end extending longitudinally to said socket and separating the end portion of the holder into

two parts, a cutter blade seated in said slot and having a cutting edge disposed within 40 the socket, shoulders at the inner end of the slot engaging the inner end of the cutter blade to centralize the same with respect to the socket and means for clamping the two separated end portions of the holder together upon the blade therebetween.

7. A lead sharpener for clutch pencils comprising a blade holder having a longitudinally extensive substantially cylindrical socket in one end thereof provided with 50 rigid longitudinally extending walls to embrace and confine the casing portion of a pencil and with a lead receiving guide at the inner end of said socket in axial alignment therewith whereby the entire point end 55 of a pencil inserted in said blade holder is rotatably centralized by the engagement of the pencil casing in the longitudinal socket and the protruding lead in the lead guide at the inner end of said socket and 60 relative angular movement of the pencil and sharpener are prevented by engagement of the pencil casing with the rigid confining and supporting walls of the socket surrounding the pencil casing and the supporting 65 of the lead in the lead guide, independently of any support afforded by a cutting blade, and a plurality of cutting blade edges in the blade holder, at the innermost end of the lead guide, disposed in line with 70 said lead guide to thereby operate upon the lead protruding from the lead guide in the relative rotation of the pencil in the sharpener.

EDWARD W. HILL.
